FLAT SCREEN

Donald M. Waterous, Brantford, Ontario, Canada, assignor to Waterous, Ltd., Brantford, Ontario, Canada, a corporation of Canada

Application July 29, 1936, Serial No. 93,173
In Canada February 14, 1936

5 Claims. (CL 92—32)

This invention relates to flat screens particularly applicable for screening paper pulp.

The main object of the invention is to provide a construction of this character made up of a combination of parts which will permit of easier 5 operation than other known constructions and will provide for less wear and longer life, as well as facilitating replacement.

More specifically, the objects of the invention 10 are:

1. To provide a construction relieving the eccentric drive bearings from the weight of the diaphragm plate, thus confining the eccentric to its proper function of vibrating the diaphragm.
- 15 2. To provide an operating unit for screens of this type which may be applied as a unit to old types of machines, thus to provide them with new and improved facilities when replacement is necessary.

20 3. To provide a structure that can be readily repaired and kept in substantially continuous operation even though the eccentric drive of one or more units goes out of order.

With these and other objects in view the invention consists essentially in one phase, of a flat 25 screen including a conventional vat carrying a screen diaphragm and diaphragm actuating plate arranged in operative relationship, the latter having connected thereto an operating member in which the diaphragm plate has associated therewith resilient means for relieving the weight 30 of the plate from the operating member. In another phase the invention concerns a complete and efficient drive for flat screens which may be 35 readily applied generally to flat screens as a drive replacement and which includes novel combinations and arrangements for facilitating operation in which the foregoing feature preferably forms a part, as described in the following specification and illustrated in the accompanying drawings which form part of the same.

40 In the drawings:

Fig. 1 is a front elevation partly in section of the apparatus according to the present invention;

45 Fig. 2 is a top plan view;

Fig. 3 is a transverse section taken through the apparatus;

Fig. 4 is a fragmentary longitudinal section;

Fig. 5 is an enlarged detail of one of the eccentric driving members;

Fig. 6 is a view similar to Fig. 5, but showing a modification; and

Fig. 7 is a view taken at right angles to Fig. 6.

50 Referring to the drawings A indicates the device as a whole, which includes the supports 10

which carry the vat 11. Within the vat is mounted the conventional screen 12 carried on suitable supports 13 and 14 below which extends the usual diaphragm 15. Below the screen the vat framework is divided by partitions 16. In between each pair of partitions the diaphragm is connected to a diaphragm operating member B which may be the structure as shown, including a wooden facing 17 adapted to connect with the diaphragm and which is secured to the diaphragm plate 18, the diaphragm being continuous and passing through the partitions 16 to connect with the adjacent diaphragm operating members. The screen operates in the ordinary manner, the stock being flowed into the vat above the screen 15 and upon vibration of the diaphragm the fine pulp is sucked through the screen during the downward movement of the diaphragm whereas any coarse or large particles which tend to clog the openings in the screen are dislodged upon the 20 upward movement of the diaphragm.

During operation the screened stock is carried away from the vat through the discharge outlet 19 provided to one side of the vat which communicates with a discharge trough 20 over a dam 25 21, the latter being employed to maintain the desired level in the vat.

An important feature of the invention resides in a means for relieving the driving member for the diaphragm plate of the weight of the latter 30 so that the drive is confined to its normal function of vibrating the diaphragm and does not have, therefore, the weight of the plate imposed upon the bearings. This feature will be described along with the general description of the drive 35 and mountings hereunder.

The driving unit preferably includes a longitudinally extending bridge-tree or main trough-like support 22 which extends between and is suspended from the main supports 10, see particularly Fig. 1. It will be noted that the bridge-tree is provided with suitable flanges 22^a resting upon the transversely extending feet 23 of the main supports 10 to which they are bolted as at 24. The troughlike portion 25 of the bridge-tree or 40 longitudinal support is designed to accommodate the drive shaft 26 and bearings therefor 27 as well as the eccentrics 28 for the diaphragm plate operating member 29 and other enlarged parts connected with the drive shaft. Projecting from 45 the bridge-tree or longitudinal support are suitable pedestals or the like 30, see Fig. 3, upon which are mounted brackets or secondary frame members 31 which extend transversely to the extent of the width of the apparatus and assist in 50 55

the support of the vat structure. As may be noted particularly from Fig. 1, a pair of brackets flanks the operating member for each diaphragm plate and carried on the brackets in a position to register with and contact the diaphragm plate 18 are rubber cushion members 33. These resilient members projecting from the bracket therefore take the weight of the diaphragm plate and thus relieve the bearing in the eccentric operating member for the diaphragm plate so that the bearing and eccentric are called upon only to vibrate the diaphragm. The mounting of the cushions or resilient means 33 includes an adjustment 34 whereby the proper tension can be applied to carry the particular weight of the parts. Instead of rubber cushions other resilient means such as springs might be employed.

It will be apparent, therefore, that this development introduced to an old construction of screen or coupled with a new structure will provide a much more efficient development which will permit of easier operation and provide for less wear and longer life of the structure.

The drive as a unit also forms a salient feature of the invention as a combination alone or coupled with the weight relieving structure for the driving eccentrics. It will be apparent that a driving unit composed of the main supports 10 or other convenient general supporting structure coupled with the cross support or bridge-tree, the driving shaft 26, brackets 31 and eccentrics is readily mountable as a unit to fit into a new construction for which the drive has been built or old structures which require a drive replacement. In this combination it will be noted that the drive shaft is formed in sections united in driving engagement by couplings 35 and each operating member 29 for each diaphragm plate, which takes the form of an eccentric directly connected between the shaft and the diaphragm plate, is positioned on one of said sections. Consequently, if for any reason the operating member or eccentric 29 for any plate becomes broken or ceases to function properly, the section of shafting carrying the eccentric can be readily removed and a plain piece of shafting substituted in place thereof. Thus, the line of screens can be run with only the diaphragm section operated by the eccentric which has been removed being out of operation. Moreover, it will be noted that whereas each diaphragm plate is in direct connection with the drive shaft through a single eccentric 29, the plate is so formed to provide a connection for one end of the eccentric at the center of the plate. Thus, the whole connection is well balanced and with the employment of few operating parts the plates are easily and smoothly actuated.

The further means in the driving combination will be noted upon considering the main drive shaft bearings 21 which are carried in collar oiling bearings which form part of the bridge-tree 22. Thus, the bearings can not get out of line as they are all part of the one casting.

It will be noted that in the preferred form of construction the rubber cushioning elements are supported from one end by cup-like members carried in the brackets, the opposite end of the elements being received in sockets attached to the diaphragm plates. The adjustment for varying the tension in the preferred form of structure, it will be seen, takes the form of a screw-threaded shank connected to the cup members, the shank being adjustable in the brackets.

In Figs. 6 and 7 there is shown a modification whereby the utmost cheapness of construction and ease of repair are made possible. The eccentric 29 is provided with a lug 50, to which by means of bolts 51 there is attached a flexible strap 52, which is attached to a lug 53 on diaphragm 18 by means of bolts 54. Since resilient cushions or springs 33 carry the weight of the diaphragm and there is no function for eccentric 29 other than to pull down on the diaphragm, the strap can be of any flexible material possessing sufficient tensile strength, such as a steel spring, canvas, or processed textiles.

It will be apparent from the foregoing that a very practical and comparatively simple development has been provided under the present invention which will attain the objects sought.

Various modifications may be made in this invention without departing from the spirit thereof or the scope of the claims, and therefore the exact forms shown are to be taken as illustrative only not in a limiting sense, and it is desired that only such limitations shall be placed thereon as are disclosed in the prior art or are set forth in the accompanying claims.

I claim:

1. In a flat screen including a vat, a screen, a diaphragm and a diaphragm plate, all arranged in operative relationship, a diaphragm operating eccentric and means to rotate the same, and a flexible strap rigidly attached at its ends to said eccentric and to said plate to depress said plate, and resilient means coacting with said plate for supporting said plate and for returning said plate to its uppermost position.

2. In a flat screen including a vat, a screen, a diaphragm and a diaphragm plate, all arranged in operative relationship, a diaphragm operating eccentric and means to rotate the same, a flexible strap rigidly attached at its ends to said eccentric and to said plate to depress said plate, and resilient means coacting with said plate for supporting said plate and for returning said plate to its uppermost position, said resilient means comprising a plurality of members placed under compression by said diaphragm operating member.

3. In a flat screen including a vat, a screen, a diaphragm and a diaphragm plate, all arranged in operative relationship, a diaphragm operating eccentric, and means to rotate the same, a flexible strap rigidly attached at its ends to said eccentric and to said plate to depress said plate, and resilient means coacting with said plate for supporting said plate and for returning said plate to its uppermost position, said resilient means comprising a plurality of members placed under compression by said diaphragm operating member and means variably to place said members under compression in accordance with the weight of said plate.

4. In a flat screen: a vat, a screen therein, a frame supporting said vat, a bridge member supported by said frame, a secondary frame supported by said bridge member, resilient supporting means carried by said secondary frame, a diaphragm and a plurality of diaphragm plates supported by said resilient means in operative relationship to said screen, said resilient means permitting limited movement of said diaphragm and diaphragm plates relative to said screen, a rotatable drive shaft comprising a plurality of axially aligned sections journaled in said bridge member, a plurality of eccentrics respectively carried by and rotatable with said sections, a

5 plurality of flexible straps operatively connecting said diaphragm plates to said eccentrics, and detachable coupling members axially connecting said drive shaft sections whereby a section of
5 said drive shaft and an eccentric may be removed and replaced by a new section of drive shaft.

10 5. In a flat screen: a vat, a screen therein, a frame supporting said vat, a bridge member supported by said frame, a plurality of brackets supported by said bridge member, resilient supporting means carried by said secondary frame, a diaphragm and a plurality of diaphragm plates supported by said resilient means in operative
15 10 relationship to said screen, said resilient means supporting said diaphragm plates in their upper-
15

most position and yielding to permit limited downward movement of said diaphragm and diaphragm plates relative to said screen, a rotatable drive shaft comprising a plurality of axially aligned sections journaled in said bridge member, an eccentric carried by each of said sections, a flexible strap operatively connecting each of said diaphragm plates to one of said eccentrics whereby said drive shaft operates to move said diaphragm plates as permitted by said resilient supporting means, and detachable coupling members axially connecting said drive shaft sections whereby a section of said drive shaft and an eccentric may be removed and replaced by a new section of drive shaft.

DONALD M. WATEROUS.
